UNITED STATES PATENT OFFICE.

HARRY BALL, OF WORCESTER, MASSACHUSETTS, ASSIGNOR TO WORCESTER MANUFACTURING COMPANY, OF WORCESTER, MASSACHUSETTS, A CORPORATION OF MASSACHUSETTS.

DOOR-CHECK.

1,103,648.

Specification of Letters Patent. Patented July 14, 1914.

Application filed July 25, 1910. Serial No. 573,672.

To all whom it may concern:

Be it known that I, HARRY BALL, a citizen of the United States, residing at Worcester, in the county of Worcester and Commonwealth of Massachusetts, have invented 5 a new and useful Improvement in Door-Checks, of which the following is a specification accompanied by drawings forming a part of the same.

10 My invention relates to that class of door checks in which the tension of a spring is applied to a spindle from which a radial arm extends suitably connected with a hinged door casing or other suitable support 15 for the purpose of closing the door when open, the movement of the spindle and arm being usually retarded by forcing a body of air or liquid through a restricted passage.

The construction and operation of this 20 class of door checks will be well understood as the same are in common use.

The objects of my present invention are to apply to the above class of door checks a latching mechanism by which the movement 25 of the radial arm may be interrupted at any desired point and the door held either partially or wide open against the tension of the spring, and also to provide means for relieving the door from the tension of the 30 spring when the door is fully closed to enable an electric door opener, of the kind now in general use, to be employed with doors which are closed by spring actuated door checks, and further to enable the operator 35 to conveniently render the latching mechanism operative or inoperative at will and also to enable the stops to be conveniently adjusted by the operator and I accomplish these objects by the construction and arrangement of parts as hereinafter described 40 and illustrated in the accompanying drawings, in which—

Figure 1 represents a side view of a door check embodying my improvements. Fig. 2 is a top view of the same. Fig. 3 represents the under side of the radial arm, partly in section to disclose the spring actuated latching bolt. Fig. 4 is a detailed sectional view of a portion of the case, showing the spring 45 actuated locking bolt for adjusting the latching mechanism, and Fig. 5 is a central 50 sectional view of the upper portion of the

case and the adjustable disks thereon which are engaged by the latching bolt.

Similar reference characters refer to similar parts in the different figures.

Referring to the accompanying drawings, 1 denotes a casing having flanges 2, 2 by which the casing is attached to a door. Inclosed within the casing 1 is a coiled spring 1^a and the usual air or fluid retarding mechanism, which need not be herein described as it is in common use. The coiled spring is applied to rotate a spindle 3 in the act of closing the door, and attached to the spindle 60 3 is a radial arm 4 having the usual connection with the door casing or other suitable support, so that the swinging of the arm 4, as the spindle 3 is rotated by the tension of the coiled spring 1^a, serves to close the door 70 with a retarded movement.

Upon the under side of the radial arm 4 is a spring actuated bolt 5, sliding in ways formed on the under side of the radial arm 4 and held in place by a pin 6 which enters a slot 7 in the bolt 5. The bolt 5 is provided with a shoulder 8, between which and the annular rim 9 of a sliding block 10 I insert a spiral spring 11. The block 10 is capable of sliding in the same ways as the bolt 5 and is provided with a concentric chamber 12 which receives the smaller end 13 of the bolt. The outer or exposed end of the block 10 projects beyond the recess to be acted upon by the cam shaped end 14 of a lever 15 pivoted at 16 upon the under side of the radial arm 4. In the position of the lever 15, as shown in Fig. 3, the block 10 lies loosely in the recess and the spring 11 is relieved entirely of tension, thereby rendering 85 the sliding bolt 5 inoperative. When the lever 15 is turned parallel with the radial arm 4, the cam shaped end 14 bears against the block 10, and compresses the spiral spring 11 so its tension will be exerted 90 against the shoulder 8 of the bolt 5.

Mounted upon the casing 1 is a cover 17, having a downwardly extended flange 18 provided with a series of notches 19 in its lower edge to receive a locking bolt 20, which 100 is forced into one of the notches 19 by a spring 21 held in a vertical recess in the case 1. The locking bolt 20 is provided with a stud 22 projecting beyond the outer side of

the case 1 which enables the bolt to be depressed by the operator and withdrawn from engagement with the notches 19, thereby releasing the cover 17 and allowing it to be adjusted on the case 1.

Mounted upon the cover 17 is a disk 23 which is adjustably held by means of a pin 24 entering one of a series of holes 25 and a hole 26 formed in the cover. The disk 23 is 10 provided at its periphery with a notch 27 adapted to be engaged by the end of the bolt 5 whenever the radial arm 4 in opening the door is brought into proper position to bring the bolt 5 into alinement 15 with the notch 27. The notch 27 affords sufficient frictional resistance to the bolt 5 to check the action of the actuating spring by which the spindle 3 is rotated and hold the door in any given position according to 20 the position of the notch 27.

On the periphery of the flange 18 is a shoulder 28 and the end of the bolt 5 is downwardly extended, to form a lip 29, Fig. 1, adapted to engage the shoulder 28. The 25 frictional resistance offered by the shoulder 28 to the end of the bolt 5 is sufficient to counteract the tension of the actuating spring connected with the rotating spindle 3. In operation the shoulder 28 is designed 30 to relieve the door from the tension of the spring just before the free edge of the door is completely closed, usually within about one eighth of an inch of the complete closure of the door, the momentum of the door 35 being depended upon to move the door through the remaining one eighth of an inch; or to bring the free edge of the door against the door jamb for the purpose of enabling the door check to be employed in 40 connection with the pivoted retaining latch of an "electrical door opener," such as is in general use in apartment houses and other places where the locking mechanism of the door is to be released from a distance.

In applying the door check the shoulder 45 28 is placed in proper position to be engaged by the bolt 5 when the free edge of the door is within about one eighth of an inch of being closed, while the notch 27 is placed in 50 proper position by the adjustment of the disk 23 to hold the door open at any desired distance. If the door check is not used upon a door having what is known as an electrical door opener, the shoulder 28 may be adjusted 55 in proper position to hold the door open a few inches by withdrawing the locking bolt 20 and turning the cover 17 to cause the locking bolt 20 to engage another of the notches 19, and the disk 23 may then be readjusted to hold the door still, further open.

The use of the notch 27 and the shoulder 60 28 for holding the door open at different degrees enables the door to be held wide open for free passage, or to stand ajar a few

inches for the purpose of ventilation. Whenever the door is held by the engagement of the bolt 5 with either the notch 27 or shoulder 28, it may be readily released by a slight pressure upon the free edge of the door, 70 when the tension of the actuating spring connected with the oscillating spindle 3 will be permitted to close the door. When desired, the notch 27 may be placed in position to be engaged by the bolt 5 when the door is 75 in its extreme open position, allowing the door to be opened sufficiently for passing without engaging the notch 27, allowing the notch to be utilized only when it is necessary to hold the door in its extreme open position. 80 By adjusting the shoulder 28 in a suitable position to hold the door slightly ajar, ventilation can be maintained as long as desired, when the bolt can be released by hand and the door allowed to close; for example, 85 the doors of telephone booths may be caused to stand permanently ajar when not in use, thereby ventilating the booth.

I am aware that it is not new to restrain the swinging movement of the radial arm 4 90 by means of a yielding latching mechanism between the arm and the casing of the door check, but such devices, so far as I am aware, are more or less difficult of access and adjustment. Door checks of the class described are employed in situations where it is desirable that the positions in which the door is held open by the latching mechanism should be varied from time to time, and it is one of the objects of my present invention 100 to enable this to be conveniently accomplished by the operator. This is done by engaging one of the stops on the cover of the casing by the sliding bolt 5, depressing the bolt 20 by means of the stud 22 until the flanged cover is released, and then swinging the door and cover to a desired position and allowing the latter to be reengaged by the spring actuated bolt 20. It frequently occurs that it is desirable to entirely relieve 110 the door of its latching mechanism, allowing the door to be always automatically closed when opened to any extent. This is accomplished by my improvement by simply rotating the cam on the under side of the 115 radial arm, thereby relieving the tension of the spiral spring 11.

I claim,

1. In a door check, a casing, a cover adjustably attached to said casing and provided with a stop on its periphery, a radial arm adapted to be connected with a door casing, a bolt sliding in ways on the under side of and parallel with said radial arm, a spring applied to force said bolt against the 125 periphery of said cover, and means for releasing said bolt from the tension of said spring.

2. In a door check of the class described, a casing, a cover adjustably attached to said 130

casing and having a shoulder on its periphery, a radial arm adapted to be connected with a door casing, a radially sliding bolt held on the under side of said arm, a slide-
5 able block, a spring interposed between said bolt and said block, and a cam bearing against said block to force it against said spring.

3. In a door check of the class described,
10 a spring actuated swinging arm adapted to be connected with a door casing, a stop adjustably held by the casing of the door check, a bolt slideable in ways on the under side of said swinging arm, a spring bearing against
15 said bolt to force it endwise, and a rotatable cam arranged to compress said spring.

4. In a door check of the class described, a casing, a flanged cover for said casing provided with a series of notches on the lower
20 edge of its flange, a vertically slideable bolt held by said casing, a spiral spring applied to said bolt to force it into one of said notches, a stud projecting from the side of said bolt, a swinging radial spring actuated

arm, and a locking mechanism between said 25 arm and said cover.

5. In a door check of the class described, a casing, a radial spring actuated swinging arm, a pair of stops independently adjustable on said casing in different horizontal 30 planes, a slideable bolt held on the under side of said arm in the plane of one of said stops, and a spring for forcing said bolt toward the casing, said bolt having a lip extending into the plane of the other of 35 said stops.

6. In a door check of the class described, a casing having a pair of stops in different horizontal planes, a swinging spring actuated arm, and a slideable spring actuated 40 bolt carried by said arm and adapted to engage either of said stops.

Dated this 23rd day of July 1910.
